CLAIM

The ornamental design for an ornamental keto plate with securable lid, as shown and described.

DESCRIPTION

FIG. 1 is a top perspective view of an ornamental keto plate with securable lid showing my new design;

FIG. 2 is a front elevational view thereof, the rear, left and right elevational views being identical;

FIG. 3 is a top plan view thereof;

FIG. 4 is a bottom plan view thereof;

FIG. 5 is a top perspective view of the ornamental keto plate with the securable lid removed;

FIG. 6 is bottom perspective view of the ornamental keto plate with the securable lid removed;

FIG. 7 is a front elevational view of the ornamental keto plate with the securable lid removed, the rear, left and right elevational views being identical;

FIG. 8 is bottom plan view of the securable lid with markers showing the FIG. 8 and FIG. 9 drawings are viewing direction; and,

FIG. 9 is a top plan view of the ornamental keto plate with the securable lid removed.
